UNITED STATES PATENT OFFICE.

GEORGE M. HAAS, OF NEW YORK, N. Y., ASSIGNOR TO THE AUTOMATIC TARGET MACHINE COMPANY.

TARGET APPARATUS.

No. 820,569.

Specification of Letters Patent.

Patented May 15, 1906.

Application filed July 7, 1905. Serial No. 268,694.

To all whom it may concern:

Be it known that I, GEORGE M. HAAS, a citizen of the United States, residing in the borough of Manhattan, in the city, county, and State of New York, have invented certain new and useful Improvements in Target Apparatuses, of which the following is a specification.

This invention relates to the class of targets or apparatuses wherein the spot or object aimed at by the marksman is indicated electrically and wherein a firearm or something which simulates a firearm—as, for example, a gun or pistol—is employed, but no explosive or projectile is used.

A target apparatus belonging to this general class is described and claimed in the United States Patent No. 679,325, granted to The Automatic Target Machine Company July 30, 1901, and this patent may be referred to as fairly illustrating the art to which the present invention belongs. It may be explained that in the said patent the target aimed at by the marksman is of the usual form, having a bull's-eye and rings or zones and wherein only the success is signalized, this being effected by an indication visible to the eye.

The object of the present invention is to provide a target apparatus otherwise similar in principle to that shown in the before-mentioned patent, but furnished with means for signalizing to the marksman a "miss" as well as a "hit." The miss may be signalized by sound, as with a phonograph, or by sight or semaphorically, as herein shown.

In the accompanying drawings, which illustrate an embodiment of the invention, Figure 1 is a somewhat diagrammatic side elevation of the apparatus on a relatively small scale. Fig. 2 is a plan view of the contact-disk, and Fig. 3 is a cross-section of same at line x² in Fig. 2. Figs. 4 and 5 are somewhat diagrammatic face views of the target and the electrical connections with the contact-plate, the former showing the normal condition and the latter the condition when a miss contact has been made. Fig. 6 is a horizontal section through the sign above the target-stand.

Referring primarily to Fig. 1, A designates the simulated firearm, here represented as a

pistol, mounted in a universal manner on a stand B in a known way. C designates the target-stand as a whole. D designates as a whole the contact plate or device in the stand B, and E designates the drop-contact or selector, the movements of which are controlled by the firearm in aiming and by the trigger thereof in "firing." G designates a battery or other source of electricity, and W designates the wires leading from the stand B to the target-stand C, as will be hereinafter more fully explained.

In the target-stand C (which may be in the nature of an upright frame with a glass front plate) are mounted targets of various kinds. (Seen best in Figs. 4 and 5.) As here shown, there are nine of these targets variously disposed and numbered 1, 2, 3, 4; 5, 6, 7, 8, and 9. There may, however, be one or more of such targets, and it is not important to this invention of what kind they are, except that when the marksman aims correctly at one of them and pulls the trigger an electric circuit will be completed through that particular target, and the fact of his success will be signalized to the marksman in some way electrically—as by the ringing of a bell, the lighting of an incandescent lamp, or the like.

It may be explained that some of these targets are or may be mechanical and are operated each by an electromagnet energized by the completion of the circuit through said magnet when the trigger is pulled.

The metal contact-plate F of the device D has set in it at the proper points and insulated from the said plate itself certain metal contact disks or pieces numbered 1^a, 2^a, 3^a, 4^a, 5^a, 6^a, 7^a, 8^a, and 9^a, each of which is electrically connected by a wire w with the target or target element having the corresponding number at the target-stand, and all of the targets are connected through the return-wire W and the battery G with the selecting-contact E. This latter, by means fully described in the before-mentioned United States Patent No. 679,325, is caused in the aiming of the firearm to move over the contact-plate F, but above and out of contact therewith. When the trigger is pulled, however, it drops into contact with the plate F or disks therein. If the marksman has aimed, for example, at the target numbered 8, which is a bell on a

clock, as herein shown, and the aim has been correct, the selecting - contact E will fall, when he pulls the trigger, into contact with the metal disk 8^a, and this will complete the circuit through the target 8 and ring the bell. If, under the circumstances named, the aim of the marksman is not good, the contact E will then fall on some part of the metal plate F, and this will have the effect to complete a circuit through one or more incandescent lamps H, Fig. 6, disposed at the top of the target behind a translucent sign I. The wire w' constitutes, with the return-wire W, the circuit through the lamps H. The sign I will be or may be of letters in opaque material or paint on a transparent plate i, as glass, disposed in front of the lamp or lamps and behind a plate i' of translucent glass. Such a sign under normal conditions will exhibit no inscription; but when the lamp or lamps H are lighted the sign will be illuminated and the inscription will appear plainly, as in Fig. 5, and inform the marksman that his shot has missed. The inscription on the sign in Fig. 5 is "You Missed It;" but any suitable phrase may be employed to indicate a "miss."

It will be understood that in the electric installation the several numbered targets will connect with the return-wire W in the usual way. This common connection or cable is indicated diagrammatically in Figs. 4 and 5 by the wires w'.

The purpose of the invention is to signalize to the marksman not alone his successes, but his failures also, and this is important in order to satisfy him that the apparatus is in order. Obviously this failure of the marksman may be signalized in various ways and by various means and the present invention is not limited to the particular indicating means herein illustrated, as such may be constructed in various ways without departing materially from the present invention. There will be an automatic circuit-breaker, so retarded as to break the circuit a convenient time after the trigger has been pulled. Such a mechanism is not new, and one device for the purpose is described in the before-mentioned patent, No. 679,325. This device, in the case of a miss, will leave the sign I announcing the miss illuminated for a few seconds.

In order to clearly distinguish the present invention from that shown in the before-mentioned patent, No. 679,325, it should be noted that in said patent a single target is shown, and whatever point on this target is aimed at there will be a visible indication of the result, showing location; but if the marksman misses the target altogether there will be no indication. In the present case there is a target-field on which are grouped the objects or targets, either of which may be aimed at, and if the marksman fails to aim correctly at either of these objects his aim will fall on the

field. This results in a miss, which according to the present invention is specially signalized in a manner to inform him that he has missed, but the locality of his aim is not indicated. He merely learns that he has missed the target or object altogether. This is important, as has been hereinbefore explained.

The words "firearms" and "simulated firearm" are herein meant to include any device capable of being aimed, and by "trigger" is meant any device capable of setting the selecting-contact in operation.

Having thus described my invention, I claim—

1. A target apparatus, having a universally-mounted simulated firearm, a target-field, a group of objects on said field each of which forms a target capable of being aimed at with said firearm, and electrical means, made operative by actuating the trigger of the firearm, for indicating a "hit" when the firearm is aimed at any target on the field, and also electrical means for indicating by a special signal a "miss" when the firearm is not aimed at a target on the field.

2. A target apparatus, having a universally-mounted simulated firearm, an object to be aimed at therewith, and electrical means made operative by actuating the trigger of the firearm, which signalizes the result when the marksman shall have aimed at said object, and also electrical means which signalizes the result by illumination when the marksman shall have missed the said object.

3. A target apparatus, having a universally-mounted simulated firearm, a target to be aimed at therewith, an electric-light circuit having a lamp or lamps near the target and adapted to be completed through said lamps by pulling the trigger of said firearm, and a sign, illuminated by said lamps, said sign having on it an inscription signalizing to the marksman that he has missed the target.

4. A target apparatus, having a universally-mounted simulated firearm, a target to be aimed at, electrically-operated means adjacent to the target for signalizing to the marksman his failure to aim correctly at the target, electrically - operated means at the target to signalize to the marksman his success in aiming correctly thereat, circuit-closing devices adjacent to the firearm and made operative by pulling the trigger of the firearm, and circuits connecting the respective circuit-closing devices with the signalizing devices at the target.

5. The combination with the simulated firearm and its stand, the target-stand, and targets mounted on said stand, of a selecting-contact E, movable with the firearm in aiming, a metal plate F below the selecting-contact, contact-disks set in said plate and insulated therefrom, conductors connecting the

said contact-disks with the respective targets, an electrically-operated device adjacent to the targets for signalizing a miss, a conductor connecting said device with the plate F, a battery or generator, and a return-conductor connecting the said miss-signalizing device and the targets with the contact E.

In witness whereof I have hereunto signed my name, this 6th day of July, 1905, in the presence of two subscribing witnesses.

GEORGE M. HAAS.
